REVERSIBLE SWING HAMMER CRUSHER
WITH ADJUSTABLE BREAKER PLATESFred J. Wright, Columbus, Ohio, assignor to The
Jeffrey Manufacturing Company, a corporation
of Ohio

Application May 6, 1947, Serial No. 746,365

2 Claims. (Cl. 241—89)

1

My invention relates to a material reducing apparatus or plant of the dustless type wherein reduced material is removed from the apparatus by means of a conveyer.

It is an object of my invention to provide an improved material reducing apparatus of the hammer mill type which includes a power driven material reducing rotor and a reducing means adapted to co-operate therewith which is mounted by arms for bodily movement about parallel axes to and from the power driven rotor for changing the relationship of the co-operating material reducing surfaces of the power driven rotor and the material reducing means.

It is another object of my invention to provide an improved material reducing apparatus of the hammer mill type which includes a power driven material reducing rotor operating within a material reducing chamber and a reducing means adapted to co-operate therewith mounted upon arms for bodily movement about parallel axes to and from the power driven material reducing rotor for changing the relationship of the co-operating material reducing surfaces of the power driven rotor and the material reducing means wherein one of the arms which carries the reducing means forms a breaker wall in the material reducing chamber.

Other objects of the invention will appear hereinafter the novel features and combinations being set forth in the appended claims.

In the accompanying drawings,

Fig. 1 is a side view in elevation of a material reducing plant incorporating the features of my invention, a portion of a conveyer thereof being shown in dotted lines;

Fig. 2 is a view in section through the material reducing plant seen in Fig. 1 but with the conveyer portion shown in elevation, the section being taken on line 2—2 of Fig. 3; and

Fig. 3 is a view in section, the section being taken on line 3—3 of Fig. 2.

Briefly described, the material reducing plant 10 shown in the drawings includes an outer housing or casing 11 within which there is an inner housing, compartment or material reducing chamber 12. Within and adjacent the bottom of the inner housing, compartment or material reducing chamber 12 there is a reversible power driven material reducing rotor assembly 13. The inner housing, compartment or material reducing chamber 12 is connected with a feed chute, opening or passage 14 positioned centrally thereabove through which material is fed into the material reducing chamber 12 to be reduced

therein by the material reducing rotor 13 and walls of the material reducing chamber 12 which co-operate with the rotor 13 to reduce the material.

Below the inner housing, compartment or material reducing chamber 12 is a reduced material receiving chamber 15 into which material reduced in the reducing chamber 12 falls or is discharged. As shown in the drawings, the bottom of the reduced material receiving chamber 15 is formed by the traveling top run 16 of a power driven conveyer 17, the foot section only of which is shown.

Referring in detail to the construction of the plant 10, the outer housing or casing of the material reducing plant 10 forms the main frame 18 of the upper portion of the material reducing plant 10, which portion of the plant includes a hammer mill type grinder for reducing, breaking, grinding and otherwise reducing material fed into the material reducing plant 10. Main frame 18 includes a pair of opposite upright wall members 19 and 20 of similar shape which are connected as by welding along their bottom edges to a rectangular frame or base 21. Extending between the opposite upright wall members 19 and 20 above the rectangular frame or base 21 there is a pair of oppositely disposed connector members 22 each of which is secured to both of the opposite upright wall members 19 and 20 and to the rectangular frame or base 21 as by welding.

The opposite upright wall members 19 and 20 form end walls of the material reducing chamber 12 and of the feed chute 14 and the areas between the opposite upright wall members 19 and 20 above the connector members 22 and at each side of the feed chute 14 are closed by suitable covers 23 each of which includes an inspection opening 24 closed by a plate 25 bolted to the outside of each cover 23.

The top walls of the material reducing chamber 12 are formed of a pair of similar relatively heavy plates 26 which extend between the opposite upright wall members 19 and 20 and are welded at their ends thereto, thereby forming fixed walls of the material reducing chamber 12 and fixed members of the main frame 18. The inner or centermost edges of fixed plates 26 are each welded to a bottom side edge of the feed chute 14. Wall members 19 and 20 in those areas where they form the end walls of the material reducing chamber 12 have bolted thereto renewable liner plates 27. It may be noted here that the opposite upright wall members 19 and

26 and the top walls of reducing chamber 12 formed by plates 26 are the only wall members of the material reducing chamber 12 which are not adjustable.

That part of the material reducing plant 10 which is above the rectangular frame or base 21 is symmetrical about an upright plane, indicated at 28 in Fig. 2, which plane extends through the axis of the rotor assembly 13 and the feed chute or opening 14, therefore, a description of the right half of the material reducing chamber 12, as seen in Fig. 2, will also describe the left side thereof.

A portion of the right hand wall of the material reducing chamber 12 is formed by a breaker plate 29 which may be considered as a generally upright substantially flat arm having an inner breaker face or surface 30. Each breaker plate or arm 29 is spaced inwardly of one of the opposite side walls of the housing or main frame 18 and these breaker plates or arms 29 form opposite walls of the material reducing chamber 12 and each co-operates with the adjacent outer wall of the housing or main frame 18, or more specifically with cover members 23 thereof, to provide an air passage 36 therebetween that is more fully described hereinafter. Each breaker plate or arm 29 is pivotally carried at its upper end upon a shaft 31 which extends between and into aligned opposite openings in the opposite upright wall members 19 and 20 each of which openings is closed at the outside by a disc or plate 32 bolted to the outside of wall members 19 and 20. Breaker plate or arm 29 pivots upon and about the axis of the shaft 31 and the uppermost end of its inner or material reducing surface 30 is formed as an arc about the axis of shaft 31 so that the surface 30 will co-operate with the lower or outermost edge of plate 26 as the breaker plate or arm 29 is swung upon its pivot shaft 31 to maintain a close fit between the plate 26 and breaker plate or arm 29 in order that there will be at most only a very small gap between the plate 26 and arm 29 through which material might be thrown out of the material reducing chamber 12. Below the breaker plate or arm 29 and pivotally connected thereto by a shaft or pivot pin 33 is a material reducing chamber wall portion or member in the form of a grate 34 that forms an extension of the breaker plate or arm 29 through which it is supported. Grate 34 includes a lug or ear 35 by which it is pivotally connected through a pivot shaft, rod or pin 39 to the lower end of a pair of spaced arms 36 the upper ends of which are mounted upon a pivot shaft, rod or pin 37 which, like pivot shaft, rod or pin 31, extends between and into aligned openings in the opposite upright wall members 19 and 20 of main frame 18 which are closed by discs 38, seen only in Fig. 1.

The axes of pivot shafts, rods or pins 31, 33, 37 and 39 are parallel with respect to one another and the opposite walls 19 and 20 of the main frame 18 form fixed means supporting the pivot pins 31 and 37 about which the arms 29 and 36 swing. The lower ends of arms 29 and 36 are pivotally connected by the grate 34 which is swingable therewith whereby the fixed opposite wall members 19 and 20, arms 29 and 36, and grate 34 form, as seen in Fig. 2, a parallelogram wherein the arms 29 and 36 and the grate 34 swing between the fixed opposite wall members 19 and 20 to adjust the position of the grate 34 to and from the rotor.

In the embodiment of the apparatus shown in 75 plane 28 at least a distance A by the portion of

the drawings the spacing of the axes of the shafts 31, 33, 37 and 39 is such that the arms 29 and 36, grate 34 and the main frame members 19 and 20 operate, as seen in Fig. 2, as a parallelogram. However, it is to be understood that the spacing of the axes and lengths of the various members need not be such that the mechanism for carrying and adjusting the position of the grate be a true parallelogram. In fact, in certain instances it is advantageous that the spacing be such that the grate will not remain in the same general upright position as it is adjusted with respect to the rotor assembly 13 in order that the distance between the co-operating surfaces of the grate and rotor adjacent the heel and toe, respectively, of the grate may be changed with respect to one another as the grate is moved to and from rotor assembly 13.

Grate 34 is provided with an ear or lug 40 adapted to receive the end of an adjusting bolt 41 that extends outwardly through a bar 42 and is locked thereto by a pair of nuts 43, one of which is disposed on each side of the bar 42. Bar 42 extends between the opposite upright wall members 19 and 20 of main frame 18 and each end thereof is provided with an outwardly extending boss or trunnion member 44 (see Fig. 2) which is received in an opening in the wall members 19 and 20 of main frame 18. The openings which receive the bosses or trunnions 44 are closed at their outsides by plates or discs 45, seen in Fig. 1. Access to the nuts 43 for adjusting the position of grate 34 with respect to the material reducing rotor assembly 13 is had through the inspection opening 24 in main frame cover member or closure 23.

Within the material reducing chamber 12 and above the reversible material reducing rotor assembly 13 is a pivotally mounted material flow directing or diverting member in the form of a butterfly valve 46 which extends across the material reducing chamber 12 and has its upper end extending into the feed chute or opening 14. The material directing or diverting member 46 includes opposite walls 47 removably secured to a shaft 48 which forms the pivotal mounting means of the material directing or diverting member 46. Shaft 48 extends between the opposite upright walls 19 and 20 and is carried in aligned openings therein one of which is closed by plate or disc 49, seen in Fig. 3. It is to be noted that the axis of shaft 48 is parallel with the axis of the rotor 13 and lies in a vertical plane passing through the axis of the latter. The end of shaft 48 opposite plate or disc 49 carries a handle or lever 50 by which an operator may change the position of the material directing or diverting means 46 to cause it positively to direct or divert selectively, all of the material entering the material reducing chamber 12 through the feed chute or opening 14 into the material reducing chamber 12 toward that breaker surface 30 of that breaker plate, side wall or arm 29 with which the rotor 13 is co-operating to break or otherwise reduce the material.

It is to be noted, as seen in Fig. 2, that when the material directing or diverting member 46 is in the position shown, that portion of the material reducing chamber 12 which is to the left of the lower right hand end of the material directing or diverting member 46 is completely covered and that all of the material entering the chamber 12 through feed chute or opening 14 is positively directed to the right side of the upright

the swingable material directing or diverting butterfly valve 46 which extends below the axis of shaft 48. Since the axis of pivot shaft 48 of the material directing or diverting butterfly valve 46 lies in a vertical plane through the axis of rotor 13 the bottom, or that portion thereof which extends below the axis of shaft 48 will swing through the said vertical plane when the position of the butterfly valve 46 is shifted for selectively positively directing all of the material entering the reducing chamber 12. The reasons for directing material into the chamber 12 a distance A beyond plane 28 toward the breaker plate or arm 30 with which the rotor assembly is co-operating to break or reduce material is fully explained hereinafter.

The handle or lever 50 by which the material directing or diverting means 46 is adjusted preferably has secured thereto a pair of ears or lugs 51 one of which co-operates in either position of the material directing or diverting means with one of a pair of ears or lugs 52 on main frame wall 19. Ears 51 and 52 include openings adapted to align with each other for receiving a locking bolt 53 for insuring that the position of the material directing or diverting means may not be accidentally or inadvertently shifted during operation of the material reducing apparatus.

Each of the opposite upright main frame wall members 19 and 20 adjacent the bottom of that area thereof which forms an end wall of the material reducing chamber 12 as well as the liner plates 27 carried thereby forms a circular opening 54. The openings 54 in the side wall members 19 and 20 are axially aligned and receive end flywheel members 55 of the rotor assembly 13. The outside of each flywheel receiving opening 54 of the walls 19 and 20 is closed by a circular disc or plate 56 having a central shaft receiving opening 57. Each disc or plate 56 is bolted about its periphery to a ring 58 which is welded to the outside wall of the main frame 18.

The rotor assembly 13 includes a shaft 59 the left hand end of which, as seen in Fig. 3, carries a ring 60 which co-operates with an inwardly extending peripheral shoulder formed about the opening 57 in plate 56 to form a labyrinth type lubricant seal. The left hand end of shaft 59 also includes a shouldered portion which receives a self-aligning anti-friction bearing 61 that is fixed upon the shouldered portion of the shaft 59 by a nut 62 which carries a removable ring 63. Bearing 61 is supported by disc or plate 56 through a cap 64 bolted to the disc or plate 56 in which there is formed a central opening having a peripheral shoulder which co-operates with the removable ring 63 to form an outer labyrinth type lubricant seal for the compartment in which the bearing 61 is carried. The outermost or left end of shaft 59 is adapted to receive a driving pulley 65, which is shown in phantom lines in Fig. 3, that is keyed to the shaft 59 by a key 66.

The right hand end of shaft 59 carries a ring 60' which co-operates with an inwardly extending peripheral shoulder formed about the central shaft opening in the right hand disc or plate 56 and the right hand end of shaft 59 is carried by the right hand disc 56 through a self-aligning anti-friction bearing 61' in a cap 67 that is similar to cap 64 except that it is not provided with a central opening because shaft 59 does not extend through the cap 67. Bearing 61' is not fixed to the rotor shaft 59 in order that shaft 59 may move axially in bearing 61' and for permitting bodily removal of the rotor assembly 13 through

the left hand opening 54 as fully described hereinafter. Shaft 59 includes a heavy center portion 68 which is provided at each of its ends with a shoulder 69 against which the heavy flywheels 55 are clamped by three clamping members in the form of rods or tie bolts 70. Between the flywheels 55 the body of the rotor assembly 13 includes a plurality of triangular plates 71 spaced apart by spacer collars 72 carried upon the clamping members or rods 70. The apices of triangular plates 71 are aligned and bored to form three axially aligned bores through the body of the rotor 13, each adapted to receive a pin, rod or shaft 73 upon which there are pivotally or swingably mounted hammers 74 which extend outwardly from between the triangular plates 71. The ends of the pins or shafts 73 are received in and held against axial movement by sockets formed in the flywheels 55. Preferably each flywheel 55 is keyed to the shaft 59 by a key 75 and the triangular plates 71 are keyed to the shaft 59 by a key 76.

The hammers 74 of the rotor assembly 13 may be replaced by removing the closure disc 56 of the right hand opening 54, cap 67 and the shaft supporting bearing 61' as a unit from the wall 20 and the right hand end of shaft 59 to expose the right hand flywheel 55 which may then be removed from the rotor shaft 59 by removing nuts 77 from the ends of clamping bolts or tie rods 70. With the right hand flywheel 55 removed, pins 73 may be withdrawn from the hammers 74 and plates 71 of the rotor body and new hammers 74 may be inserted in place of the removed hammers 74 as each pin or shaft 73 is replaced in the rotor body. When the hammers 74 have been renewed the flywheel 55, disc 56, cap 67 and bearing 60 may be replaced and the machine is ready for operation. If desired, the entire rotor assembly 13 may be removed bodily from the reducing chamber 12 by removing the bolts which secure the left hand disc or plate 56 to the left hand wall 19 and withdrawing the rotor from the chamber 12 through the left hand opening 54.

While I have shown the hammers 74 as being swing hammers, it is to be understood that the hammers or elements 74 may be of any desired shape and that they need not be pivotally mounted to the rotor body.

The portion of the plant 10 above described is carried by and above a pair of spaced supports 78, herein shown as being of cast concrete. The conveyer 17 is positioned between the supports 78 and is directly below the reducing apparatus. Between the bottom of the rectangular frame or base 21 of main frame 18 and the upwardly traveling top run 16 of the conveyer 17 there is a depending boot 79 which co-operates with the walls of main frame 18 and the upper traveling run 16 of the troughed conveyer 17 to form the reduced material receiving chamber 15. Boot 79 includes a pair of inwardly downwardly sloping side walls 80 and an inwardly downwardly sloping end wall 81 each of which, adjacent its lower edge, carries a resilient strip or apron 82 adapted to ride with a light pressure upon the top surface of the upwardly traveling top run or belt 16 of conveyer 17 to seal the upwardly traveling run or belt 16 to the walls 80 and 81 so as substantially to prevent the loss or egress of materials and gas from the reduced material receiving chamber 15 between the walls 80 and 81 and the conveyer run 16.

As seen in Figs. 1 and 2, the side walls 80 of depending boot 79 extend sidewardly in the direc-

tion of travel of the upwardly traveling top run 16 of conveyer 17 to form an elongated tapering boot 83, the top member of which is formed by a plate 84 spaced above the conveyer. The bottom of boot 83 is formed by the upper traveling run of troughed belt 16 which co-operates with a depending flexible curtain 82' at the right side of boot 83 to form a variable size outlet opening therein which co-operates with the troughed traveling run 16 of the conveyer 17 and reduced material which is being conveyed thereby from the reduced material receiving chamber 15 to form a variable size substantially gas tight opening, the size of which varies with the quantity of material being conveyed upon the conveyer and which materially restricts the egress of gas from the reduced material receiving chamber 15 while permitting the troughed conveyer run 16 and the reduced material carried thereby to be conveyed from the chamber.

The opposite side walls of feed chute 14 are formed by a plurality of downwardly inwardly sloping louvre members 85 between which there are passageways that open directly into ducts or passageways 86 formed by the main frame 18, the wall members of the material reducing chamber, and the cover members 23. Passageways or ducts 86 connect at their lower ends directly with the reduced material receiving chamber 15.

It is well known that the rotor assembly of a material reducing apparatus or grinder, when operating, functions as an impeller or blower and forces air or gas out of the apparatus and that when the apparatus is reducing material the air or gas impelled by the rotor will flow out of the apparatus with material that has been reduced. Air or gas exhausting from the material reducing apparatus with the reduced material that is relatively dry creates a dusty, and frequently a hazardous condition. I provide for substantially closing or sealing the material reducing apparatus against the egress or loss of gas while conveying reduced material therefrom by a conveyer, a portion of which is in or operates within the apparatus and is adapted to receive and convey reduced material exhausted into the closed reduced material receiving chamber from the material reducing chamber through a variable size opening which materially restricts or substantially prevents the egress of gas from the chamber with or about the reduced material, and in my apparatus I have provided for the unrestricted passage of all of the air impelled by the rotor assembly back to the material reducing chamber. In the embodiment of my invention shown in the drawings the gas impelled by the rotor assembly 13 into the reduced material receiving chamber 15 is returned to the reducing chamber 12 through the passageways, ducts or conduits 86 formed by the breaker plates 23, their grates 34 and the adjacent wall of the housing or main frame 18 and the passageways between the louvres 85 into the feed chute 14 where it flows with material to be reduced into the reducing chamber 12.

Referring again to the material reducing chamber 12 and the rotor assembly 13 which is between and separates the chamber 12 from the reduced material receiving chamber 15, I have found that in material reducers or grinders of the reversible rotor type, material which is fed into the material reducing chamber to that side of the upright plane 28 which is opposite the breaker wall or surface 30 with which the material re-

ducing hammers or elements of the rotor 13 are co-operating to reduce material, will be thrown or knocked upwardly into the feed chute or opening 14, and that under certain conditions the material being thrown or knocked upwardly by the rotor and the material flowing in the chute 14 will jam in the chute and prevent or materially interfere with the feeding of material into the material reducing chamber 12. I have also found that when all of the material is caused to enter the material reducing chamber 12 to that side of the upright plane 28 which is adjacent that breaker plate or arm 29 with which the material reducing hammers or elements of the rotor are co-operating to reduce material, the clogging tendencies above described are materially reduced. I have further found that in certain instances it is desirable that material entering the chamber 12 should be deflected to or caused to be struck by the reducing elements or hammers 14 of the rotor assembly 13 to that side of the plane 28 which is in the direction of rotation of the material reducing hammers or elements of the rotor and adjacent that breaker plate or arm 29 with which the material reducing elements are co-operating to reduce material at least the distance herein designated A, which distance is at least equivalent to the width (indicated at A' in Fig. 2) of the widest material reducing element carried by the rotor 13 since, as hereinafter explained, material struck by the reducing elements or hammers 14 is knocked generally tangentially from the circle or cylinder defined by the paths of the rotating reducing elements or hammers 14 and when the material is struck by the hammers the distance A, above described, to one side of the plane 28, the material is thrown or knocked sidewardly rather than vertically upwardly into the feed chute 14.

It will be seen that when the rotor assembly 13 is being driven, the material reducing elements thereof define a cylinder (indicated by phantom line 94 in Fig. 2) and that material which comes against or within the periphery of cylinder 94 will be reduced by impact and knocked generally tangentially from the cylinder by the hammer elements 14. I have further found that when material fed into the material reducing chamber 12 is deflected sidewardly in the direction of rotation of the rotor at least to the point of tangency of a plane tangent to the cylinder 94 defined by the moving reducing elements of the rotor and intersecting the breaker surface 30 of the working breaker wall or arm 29 with which the hammer elements are co-operating to reduce material at most at a right angle above the tangent plane and the generally upright breaker surface 30, that even when sticky material such, for example, as moist iron ore is being reduced, there is substantially no tendency of the material to clog the feed chute or opening 14.

Referring to Fig. 2, the tangent plane above described is indicated at 87, the point of tangency with the cylinder defined by the moving reducing elements is indicated at 88, and the angle between the tangent plane 87 and the working breaker surface 30 is indicated at B. Dotted line 89 indicates the left boundary of a stream of material entering the material reducing chamber 12 through the feed chute or opening 14 which has been deflected by the material directing or diverting member 46.

A worn hammer element is indicated in dotted lines in Fig. 2 at 90, which hammer has been worn by impacts with material in the reducing

chamber. I have found that each of the hammers wears so that the working or front face 91 thereof which strikes the material wears to a curved surface, such as indicated at 92, and as the original sharp corners of the hammers wear to form the curved surface there is a tendency for them to knock or throw material which they strike sidewardly and outwardly from the rotor, thus, as seen in Fig. 2, when the hammers are new they will throw the material tangentially therefrom toward the breaker surface 30 with which they are co-operating substantially at the acute angle B indicated in Fig. 2 of the drawings and as the hammers gradually wear, the material is thrown outwardly and upwardly against the breaker surface 30 with the angle B gradually approaching a right angle, the upward movement being in proportion to the amount of wear of the hammers. When the material is deflected by the material directing or diverting means 46 to the point of tangency 88 material which is thrown by the worn hammers will be thrown against the breaker surface 30 substantially at a right angle thereto and therefore not in a path which will cause material entering the reducing chamber 12 through the feed chute or opening 14 to become jammed in the feed chute or opening 14 thereby substantially completely eliminating the detrimental effect of an accumulation of material within the feed chute or opening 14. It will, of course, be seen that the material being thrown directly against the breaker surface 30 by the rotor will prevent major accumulations of material thereon and within the material reducing chamber 12.

The co-operating ears or lugs 51 and 52 associated respectively with main frame wall 19 and handle or lever 50 of the material directing or diverting member 46 preferably also form electrical circuit breakers, not shown, which are connected into the power supply lines of the electric motor, not shown, which drives the rotor.

The circuit breakers are connected into the power supply lines so as to reverse the direction of operation of the driving motor in accordance with the position of setting to which the material directing or diverting member 46 is swung by the handle or lever 50, that is, when the material directing means is swung to the position shown in Fig. 2 the power supply lines are connected to the driving motor so that it will operate in a direction to drive the rotor assembly 13 in a clockwise direction and when the material directing or diverting member is swung to the position in which it directs material to the left, as seen in Fig. 2, the power supply lines to the motor will be reversed by the circuit breakers of which ears or lugs 50 and 51 form parts to drive the rotor assembly in a counter-clockwise direction. It will be seen that because of the described electrical circuit, the direction of rotation of the rotor assembly 13 is determined by the position of the material directing or diverting member 46.

In operation, with the rotor assembly 13 being driven at reducing speed, material to be reduced is fed into the reducing chamber 12 through the feed chute or opening 14 wherein it is reduced and discharged into the reduced material receiving chamber 15. It may be noted here that the cross bars or plates 93 of each grate 34 are so arranged that the planes of their outside surfaces 95 are substantially tangent with the cylinder 94 defined by the rotating hammers 74 of the rotor assembly 13. Because material is thrown generally tangentially by the hammer elements, re-

duced material which is thrown toward the grates 34 may pass directly through the spaces between the bars or plates 93 without clogging the passageways between the bars or plates 93 of the grates 34. Material which is discharged into the reduced material receiving chamber 15 falls upon the upwardly moving top run or belt 16 of the conveyor 17 which is within the reduced material receiving chamber 15 and is conveyed thereby sidewardly through the boot 83 and through the variable size discharge opening therein which is formed by the flexible curtain 82', which curtain preferably drags or rides upon the top of the material being conveyed in the troughed belt 16 and materially restricts or seals the reduced material receiving chamber 15 against the egress of air or gas which is being impelled by the rotor assembly 13. The air or gas which is impelled by the rotor assembly 13 flows upwardly in the ducts 86 which are in communication with the reduced material receiving chamber 15 and enters the feed chute or opening 14 through the passages between the louvers 85 where the air flows downwardly in the feed chute or opening 14 and is diverted sidewardly by the material directing or diverting means 46 as it flows back into the reducing chamber 12. This feature of my material reducing apparatus is particularly advantageous in that it tends to reduce air or gas pressure within the reduced material receiving chamber 15 and to reduce the horse power required to drive the apparatus since all of the air or gas which is caused to flow by the rotor assembly 13 is re-circulated.

The positions of the grates 34 may be adjusted with respect to the material reducing elements of the rotor assembly 13 to change or alter their positions with respect thereto for producing ground material of different size ranges. When one side of the material reducing hammer elements 74 becomes worn, the direction of operation of the apparatus may be reversed which is substantially the full equivalent of renewing the hammers 74 since those surfaces which were the backs of the hammers now become the working faces thereof. It will also be seen that with my apparatus the right grate, as seen in Fig. 2 for example, may be adjusted to such position with respect to the rotor 13 that when the rotor is driven in a clockwise direction the material will be reduced or ground to a relatively fine condition and that the grate on the left side of the machine is inoperative. The grate on the left side of the machine may be adjusted to cause the reducing apparatus to produce a coarser finished product and thus by merely reversing the direction of operation of the machine it may be caused to produce selectively a relatively fine or a relatively coarse finished product.

It will also be seen that as each of the grates 34 is adjusted, the upright angular position of its supporting breaker plate, wall or arm 29 will change and that as the grate 34 is adjusted away from the rotor assembly 13, its supporting breaker plate, wall or arm 29 will move to a position which is more nearly vertical. This is advantageous because the more nearly vertical the position of the breaker wall or arm 29, the greater is its tendency to deflect the material thrown against it by the hammer elements 74 back into the path or cylinder 94 defined by the rotating hammers.

Obviously those skilled in the art may make various changes in the details and arrangement of parts without departing from the spirit and scope of the invention as defined by the claims

hereto appended and I wish therefore not to be restricted to the precise construction herein disclosed.

Having thus described and shown an embodiment of my invention, what I desire to secure by Letters Patent of the United States is:

1. A grinder for reducing material including means forming a main frame, a material reducing chamber, wall means forming a side wall of said reducing chamber, pivot means supporting said wall means from said main frame for swinging movement about an axis, a power driven rotor in the bottom of said reducing chamber, material reducing elements carried by said rotor adapted to reduce material by impact and crushing, grate means carried by said wall means, said grate means including a face adapted to co-operate with said reducing elements for crushing material, pivot means connecting said grate means to said wall means for movement about an axis parallel to the supporting pivotal axis of the latter, a second means co-operating with said wall means supporting said grate means from said main frame for swinging movement, pivot means connecting said second means to said main frame, and pivot means connecting said grate means to said second means, all of said pivots lying on parallel axes whereby said grate means may be moved to and from said rotor thereby changing the angular position of said wall means and the position of the grate means with respect to the material reducing elements.

2. A grinder for reducing material including means forming a main frame, a material reducing chamber, wall means forming a side wall of said reducing chamber, pivot means supporting said wall means from said main frame for swinging movement about an axis, a power driven rotor in the bottom of said reducing chamber, material reducing elements carried by said rotor adapted to reduce material by impact and crushing, grate means carried by said wall means, said grate means including a face adapted to co-operate with said reducing elements for crushing material, pivot means connecting said grate means to said wall means for movement about an axis parallel to the supporting pivotal axis of the latter,

a second means co-operating with said wall means supporting said grate means from said main frame for swinging movement, pivot means connecting said second means to said main frame, pivot means connecting said grate means to said second means, all of said pivots lying on parallel axes whereby said grate means may be moved to and from said rotor thereby changing the angular position of said wall means and the position of the grate means with respect to the material reducing elements, and adjusting means for adjusting the positions of said wall and grate means as aforesaid.

FRED J. WRIGHT.
